CLAIM

The ornamental design for a book for telephone index cards or the like, as shown and described.

DESCRIPTION

FIG. 1 is a perspective view of a book for telephone index cards or the like showing our new design;
FIG. 2 is a right end elevational view;
FIG. 3 is a left end elevational view;
FIG. 4 is a rear elevational view;
FIG. 5 is a bottom plan view thereof; and
FIG. 6 is a vertical sectional view thereof taken along section line 6—6 of FIG. 1.

Fig. 1

Fig. 6.
